UNITED STATES PATENT OFFICE.

HARRY RUTGERS PRALL, OF PHILADELPHIA, PENNSYLVANIA.

EMBROIDERING AND DARNING ATTACHMENT FOR SEWING-MACHINES.

No. 913,847.

Specification of Letters Patent.

Patented March 2, 1909.

Application filed September 25, 1908. Serial No. 454,744.

To all whom it may concern:

Be it known that I, HARRY R. PRALL, a citizen of the United States, residing at Philadelphia, in the county of Philadelphia and State of Pennsylvania, have invented 5 certain new and useful Improvements in Embroidering and Darning Attachments for Sewing-Machines, of which the following is a specification.

10 This invention relates to embroidering and darning attachments adapted to be attached to the needles and needle bars of sewing machines, and particularly to those attachments which comprise a resilient coil designed to 15 take the place of the ordinary presser foot and to be attached directly to the reciprocating needle bar so that as the needle rises and falls the work is alternately held and completely released, the object of my invention, 20 being to so construct the spring coil of the attachment that it may have a maximum of compression and extension, that it may be attachable to the needle bar of a machine above the needle clamp, that it may have a 25 relatively large bearing on the work, and that it may be held concentric to the needle under all conditions. These objects I attain by the device shown in the accompanying drawings, wherein—

30 Figure 1 is a perspective view of a portion of a sewing machine head, the ordinary presser foot being removed and my attachment in position on the needle bar. Fig. 2 is an enlarged perspective of the attachment 35 detached. Fig. 3, is an under side view of the attachment.

1 designates a sewing machine head of any ordinary form or make and having the usual needle bar 2 carrying at its lower end the 40 usual needle clamp 3 having a claiming screw 4 by which the clamp is contracted to securely hold the needle to the bar.

5 designates the usual presser bar from which the ordinary presser foot has been 45 moved as unnecessary for the class of work to be done by this attachment.

My attachment is made of a continuous 50 length of spring wire 6 in the form of an elongated helical spring coil 7, the helix gradually 55 widening toward the lower end of the attachment so that when the spring is compressed one turn of the wire will approximately fit inside of the next and larger turn. The end of the wire forming the last or lowest coil or 55 turn is inwardly bent to form an eye 8 which

is concentric with the series of coils. While this eye might be a mere loop of wire, I prefer to close the loop and hold it in shape by inserting therein an eyelet 8' which is compressed on the loop. At its upper end the 60 wire 6 after having formed the smallest coil of the series which is adapted to immediately surround the butt of the needle, is bent to one side of the center of the coils and then extended upward parallel to the axis of the 65 coils as at 9, it is then bent laterally and formed into a loop 10. After forming the loop the wire is bent around three sides of an approximately square figure as at 11, the end of the wire being coiled upon itself to 70 form the final loop 12. The objects of the loops 10 and 12 are simply to provide the clamping portion of the device with rounded corners whereby it will not scratch the needle bar when the attachment is being placed 75 thereon. It will be seen that the clamp portion is open at one side and that the needle bar is adapted to be inserted through this open side, and the clamp will by its own resilience engage with said bar to hold the 80 attachment in place, while the attachment cannot move laterally because its lower end is held by the needle passing through the eye 8.

In applying the attachment the needle 13 85 is inserted through the uppermost coil and then the clamp is forced into engagement with the needle bar in the manner before stated, the device then assuming the position shown in Fig. 1. Upon a depression of the needle 90 bar the lower end of the coil is forced downward on the fabric. During the time that the needle is passing downward through the fabric the spring coil 7 is compressed. While 95 the needle is being upwardly drawn through the fabric the coil still holds the fabric to the table until after the needle has been withdrawn from the fabric, at which period the coil itself is entirely raised from the fabric which latter can then be readily moved into 100 a new position ready for a new insertion of the needle. The entire attachment is formed of a single length of spring wire, is extremely 105 cheap, easily applied and entirely effective for the work to be done.

In connection with my attachment I use the fabric stretcher 14 shown in Fig. 1. This consists of a ring of metal having a groove formed in the circumference. The split ring 15 of resilient wire is adapted to be 110

snapped over the fabric when it is in place on the ring and to clamp the fabric into the groove of the ring so that the fabric may be stretched tightly over the lower edge of the ring and then be in better condition to be operated on.

My attachment used in connection with the stretcher 14 is not only adapted for embroidery, but is peculiarly well adapted to 10 darning, as it allows stitches of any desired length or direction to be made.

Having thus described my invention what I claim as new and desire to secure by Letters Patent is:—

15 1. An attachment for sewing machines, comprising a longitudinally elongated coiled spring gradually widened toward its lower end, the lower largest coil adapted to engage upon the goods to be sewed, and the upper 20 end of said coiled spring bent into an approximate U-shape in top plan forming a clamp to secure the coil to a sewing machine needle bar.

2. An attachment for sewing machines 25 comprising a gradually widened elongated coil of spring wire, the lower end of said wire after forming the last coil being bent to form an eye located centrally in the lowest coil and adapted for the passage of a needle, the 30 upper end of said coil being upwardly extended and having means whereby it may be

attached to the needle bar of a sewing machine.

3. An attachment for sewing machines comprising a coiled spring gradually widened 35 toward its lower end, the coils of which are adapted to lie one within the other when the spring is compressed, and the lower largest coil to engage the goods to be sewed, the upper end of said coil being provided with 40 means of attachment to the needle bar of a sewing machine.

4. An attachment for sewing machines comprising a coiled spring gradually widened toward its lower end, the lower end of the 45 wire forming said coil being bent to form an eye concentric with the coils and located centrally within the lowest coil and through which the needle may pass, the upper end of said wire above the coil extending upward in 50 line with the coil, then at right angles and then laterally and inwardly to form a clamp adapted to engage around the needle bar of a sewing machine above the needle clamp.

In testimony whereof I have signed my 55 name to this specification in the presence of two subscribing witnesses.

HARRY RUTGERS PRALL.
